(57) **CLAIM**

The ornamental design for a set of wheels for a creeper, as shown and described.

DESCRIPTION

FIG. 1 is a perspective view of a set of wheels for a creeper showing my new design;

FIG. 2 is a left side elevational view thereof, the right side being a mirror image of FIG. 2;

FIG. 3 is a front elevational view thereof;

FIG. 4 is a rear elevational view thereof;

FIG. 5 is a top plan view thereof; and,

FIG. 6 is a bottom plan view thereof.

The broken line showing of a creeper is for illustrative purposes only and forms no part of the claimed design.
